CLAIM

The ornamental design for a human body detector, as shown and described.

DESCRIPTION

FIG. 1 is a front elevational view of a human body detector showing our new design;

FIG. 2 is a rear elevational view thereof;

FIG. 3 is a left side elevational view thereof, the right side view being a mirror image of that shown;

FIG. 4 is a top plan view thereof;

FIG. 5 is a bottom plan view thereof;

FIG. 6 is a front high perspective view thereof;

FIG. 7 is a rear perspective view thereof; and,

FIG. 8 is a front low perspective view thereof.

1 Claim, 8 Drawing Sheets
